Atty.

UNITED STATES PATENT OFFICE.

CHARLES S. MARSH, OF WINCHESTER, MASSACHUSETTS.

COIN-HOLDER.

No. 862,984.

Specification of Letters Patent.

Patented Aug. 13, 1907.

Application filed April 2, 1906. Serial No. 309,344.

To all whom it may concern:

Be it known that I, CHARLES S. MARSH, of Win-
chester, county of Middlesex, State of Massachusetts,
have invented an Improvement in Coin-Holders, of
5 which the following description, in connection with the
accompanying drawings, is a specification, like charac-
ters on the drawings representing like parts.

This invention relates to coin holders and has for its
object to improve the construction of the same to the
10 end that a pile of coins may be contained in a holder of
convenient form and size with the endmost coin of the
pile more or less exposed and in position to be engaged
by the thumb and pushed outward through a discharge
slot.

15 Figure 1 shows in side elevation a coin-holder em-
bodying this invention. Fig. 2 is a vertical, longitu-
dinal section of the coin-holder shown in Fig. 1. Fig.
3 is an end view of the coin-holder. Fig. 4 is a trans-
verse section of the coin-holder taken on the dotted line
20 4—4, Fig. 1. Fig. 5 is a side view of the end portion of
the coin-holder, showing the discharge slot. Fig. 6 is a
vertical section of the end portion of the coin-holder
taken on the dotted line 6—6, Fig. 3.

a represents a cylindrical barrel, which will be of any
25 suitable diameter and length. At one end of the barrel
an end cap b is formed or provided, which more or less
closes the end thereof, sufficiently at least to prevent
the coins, which are contained in the barrel, from escap-
ing. A thumb-receiving slot c is formed at the end of
30 the holder thus constructed, which extends down be-
low the end of the barrel, see Fig. 2, and cross-wise the
end cap. This slot may extend nearly or entirely
across the end cap, and is made with converging sides,
see Fig. 3, to provide a wide entrance, and the sides
35 thereof are also preferably beveled as shown in Fig. 6.

Opposite the entrance to the thumb-receiving-slot
and beneath the end cap a slot d is formed transversely
in the barrel for the discharge of the coins. A spring e
is contained in the barrel which is adapted to hold one
or more coins, arranged in a pile, in engagement with

the end cap. A plate f may be employed against which
the spring bears and upon which the coins will be
placed, or in lieu thereof any other form of rest may be
provided for the coins. The coins are thrust against
the end cap by the spring and the endmost coin of the
45 pile which is in engagement with the end cap occupies
a position opposite the discharge slot and above the
lower edge of the entrance to the thumb-receiving slot,
and will be exposed at said thumb-receiving slot, and as
it is held in a plane above the lower edge of the en-
trance to the thumb-receiving slot, it may be readily
50 engaged by the thumb and pushed out through the dis-
charge slot, the thumb engaging the edge of the coin.
By engaging the edge of the coin when pushing it out,
instead of engaging the face, it will be seen that the
55 coin will not be depressed and thereby moved out of
position to freely pass through the discharge slot.

If desired the coin holder may be made double ended,
that is to say, both ends may be constructed in the man-
ner above described to thereby receive coins of differ-
ent denominations, and in such case at the entrance to
one of the thumb-receiving-slots a projection g will be
provided, the other slot being devoid of such projec-
tion, so that a person may tell by the feeling which de-
nomination of coin he is discharging.

Having thus described my invention, what I claim
as new and desire to secure by Letters Patent is:—

A coin-holder consisting of a cylindrical barrel having
a cap at each end provided with a thumb-receiving slot
extending from below the end of the barrel crosswise the
70 end cap, and also having a slot at each end beneath the
cap, and opposite the entrance to the thumb-receiving-slot,
for the discharge of the coins, a spring contained in said
barrel for holding two piles of coins respectively against
the end caps, and a projection adjacent the entrance to
75 the thumb-receiving-slot at one end only, substantially as
described.

In testimony whereof, I have signed my name to this
specification, in the presence of two subscribing witnesses.

CHARLES S. MARSH.
